UNITED STATES PATENT OFFICE.

RICHARD GÖSSE, DECEASED, BY ADOLF GÖSSER, ADMINISTRATOR, OF MUNICH,
GERMANY, ASSIGNOR, BY MESNE ASSIGNMENTS, TO THE FIRM "STACHELBAND"
G. M. B. H., OF MUNCHEN-PASING, GERMANY.

BARBED WIRE AND THE LIKE.

Application filed September 7, 1920. Serial No. 403,754.

(GRANTED UNDER THE PROVISIONS OF THE ACT OF MARCH 3, 1921, 41 STAT. L., 1813.)

To all whom it may concern:

Be it known that I, ADOLF GÖSSER, a citizen of the German Republic, residing at Munich, Bavaria, Germany, am administrator of the estate of RICHARD GÖSSER, deceased, who invented certain new and useful Improvements in Barbed Wire and the like, for which applications have been filed in Germany, August 20, 1913, and England, September 25, 1913, of which the following is a specification, reference being had therein to the accompanying drawing.

The present invention relates to a metal band suitable as a substitute for barbed wire, which band is obtained by the stretching out of a strip of metal previously slit or cut out as by stamping.

As compared with barbed wire, the band produced according to the present invention has the important advantage that the barbs need not be formed before the moment of use. As a result there is on the one hand a considerable saving in carriage, and on the other hand wounds from the barbs are entirely obviated right up to the last moment before stretching. Particularly important, however, is the advantage that the metal band can be tightly wound, so that one is able to stock a considerable quantity in very small space. In case of need for the use of the band for military purposes, for example, each man of the troop can be provided with a considerable quantity of the band without any overloading, as the strip can easily be kept, for example, in a cooking utensil, tightly rolled up. To carry a similar length in the form of barbed wire would be inconvenient.

Fig. 1 shows at the upper part the metal band prepared with slits or cuts by stamping, and at the lower part the band stretched out.

Fig. 2 is a side view corresponding to Fig. 1.

Fig. 3 shows on a reduced scale several bands connected together but not stretched out.

Fig. 4 shows a modification.

Fig. 5 is a side view corresponding to Fig. 4.

The direction of the slits or cuts in the metal band *a* is indicated at *b*. It will be understood that the band or strip may be stamped upon other lines so long as in the stretching out of the band barb-shaped projections are formed. In order to spread out the barbs *c* in the stretched out band, the band in being stretched out can be given a twist.

To obtain several parallel and connected bands, as shown in Fig. 3, one may join together several parallel bands *a* by integral connecting pieces *d* and stretch out all the bands at the same time. The connecting pieces can be arranged in staggered relation. By means of such a band barbed fences which are particularly suitable for enclosures, can be prepared quickly and easily and at small cost.

Figures 4 and 5 show, by way of example, a modification in which the lines *b* of cutting are not continuous but are symmetrically arranged on each side of the centre line of the band or strip *a* of metal.

Having now particularly described and ascertained the nature of my said invention, and in what manner the same is to be performed, I declare that what I claim is:

1. A fence strand consisting of a metallic band provided at either side with a series of slits extending inwardly at an acute angle, and intermediate slits, the inner extensions of the said slits overlapping each other.

2. A fence strand consisting of a metallic band provided at either side with a series of inwardly extending slits at an acute angle to the edge and having extensions which overlap at the center of the band.

In testimony whereof I affix my signature in the presence of two witnesses.

ADOLF GÖSSER,
Administrator.

Witnesses:

OTTO ALBRECHT GRAF,
ERICH WERNER.
